(57) **CLAIM**

The ornamental design for a cleaning kit with case, as shown and described.

DESCRIPTION

FIG. 1 is a front, top perspective view of a cleaning kit with case, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown in an alternative position; and,

FIG. 10 is another perspective view thereof, shown in an alternative position.

The broken lines in the figures illustrate portions of the cleaning kit with case that form no part of the claimed design.
